UNITED STATES PATENT OFFICE

ERIC WILLIAM MACKAY-WHITE, OF ROSSLAND, BRITISH COLUMBIA, CANADA

INTERNAL-COMBUSTION PUMP

Application filed September 17, 1927. Serial No. 220,260.

The invention relates to improvements in pumps of the internal combustion type, such as the well known Humphrey pump, in which a column of water, by gravitational reactance from a lifting impulse imparted by one charge, causes a second charge of explosive mixture to be compressed to a degree greater than that due to the static head, and the ignition of the charge again causes the 5 column of water to rise. Because in pumps of this type, the explosive mixture is compressed by gravitational reactance of a column of lifted water, a pressure of more than about eighty pounds per square inch would cause 10 pre-ignition of the charge, and because a column giving a head of two hundred feet causes a compression of eighty-six pounds per square inch, the pump is limited to operation with 15 heads of less than two hundred feet.

20 The object of my invention is to provide means for operating a second injection device whereby a charge of fuel may be injected into air already compressed in the combustion cylinder of the pumps thus avoiding pre-ignition and so enabling a degree of compression greater than eighty pounds per 25 square inch to be used, making it possible for the pump to operate against heads in excess of two hundred feet.

30 One form of the invention is illustrated in the accompanying drawing, in which Figure 2 is a vertical elevation of the mechanism as it appears during the compression stroke in a pump of the Humphrey type before fuel 35 is injected into the combustion chamber of the pump. Figure 1 is a vertical section of the mechanism as it appears after the fuel is injected. Figure 3 is a plan view of Figure 1. Similar letters designate similar parts 40 throughout.

The movable cylinder "a" is free to move vertically on the piston block "b" which is provided with an air tight packing "c." A sleeve "d" provided with an external screw 45 thread is screwed into the passage "g" which pierces the piston block "b." A flange on the sleeve "d" serves to retain the packing "c" in place and also serves as a seat for the valve "e" by which the passage "g" may be 50 closed. The valve "b" is carried on a frame "h" which by means of an internal screw 55 thread is mounted on a projection from the port block "k." The frame "h" is of skeleton formation providing slots for the entrance of fluid therewithin and for the passage of compressed air into the cylinder "a" through the passage "g." Another projection from the port block "k" passes through the wall of the cylinder "w" in which cylinder all the mechanism is contained. The passage "l" through 60 the port block "k" connects the space within the cylinder "w" with the space outside of the same. The passage "l" may be closed by the valve "m" which is attached to the valve stem "n" which terminates in a crosshead "o," carried by two bars "r" which are attached to the walls of the cylinder "a." The crosshead "o" is provided with a pin "p" which forms an attachment for one arm of the cranked lever "q." The cranked lever 70 "q" is pivoted on a pin passing through the lug "x" which is an integral part of the frame "h." The spring "s" by means of the rod "t" connects one end of the cranked lever "q" with the lug "y" which is an integral 75 part of the frame "h." A weighted rod "v" passing through the head of the cylinder "w" (the cylinder head is not shown) is free to move in a vertical plane.

The action is as follows: A column of water rising in the cylinder "w", by gravitational reactance to the lifting impulse created by an explosion compresses the air above it and part of this air enters the cylinder "a" by 80 way of the slots in the frame "h" and the passage "g" so that the same degree of compression obtains within the cylinder "a" as in the cylinder "w". At the same time the rod "v" is raised by the pressure on its underside and comes to rest against a stop (stop is not 85 shown). The column of water rises above the valve "m" and comes to rest with the water in pump cylinder "w" at the end of the reactance flow. The air already compressed in the "w" now expands and drives the column of water downwardly before it producing a second impulse. This expansion reduces the pressure of air in the outer cylinder "w", but the air pressure in the inner cylinder "a" 90 is not reduced, it being retained by the valve 95 "b".

"e" and by the pressure on the upper side of the valve "m" which pressure acting through the valve stem "n" and the cross head "o" and the bars "r" prevents the cylinder "a" from rising. When the pressure in the cylinder "w" has reduced to such an extent that the pressure on the inner side of the head of the cylinder "a" exceeds the sum of the pressures on the valve "m" and on the outer side of the head on the cylinder "a", the cylinder "a" rises quickly drawing with it the valve "m" and opening the port "l" and thereby admits water under pressure through said port *l* from cylinder *w* to a plunger, piston diaphragm, or other suitable device provided for the actual injection of the fuel to the explosion cylinder of the pump.

The movable cylinder "a" continues to rise until the crosshead "o" strikes the valve stem "f" and raises the valve "e" thus releasing the pressure in the cylinder "a". The mechanism is now in the position shown in Figure 1. The raising of the cylinder "a" causes one end of the cranked lever "g" to rise with it since one arm of the cranked lever "g" is attached to the cylinder "a" by means of the bars "r" and the crosshead "o" and the pin "p". The cranked lever "g" is retained in this position (as shown in Figure 1) by the spring "s" and the rod "t".

The pressure being released in the cylinder "a" the said cylinder "a" falls of its own weight. When the pressure in the cylinder "w" has reduced sufficiently to permit, the rod "v" falls, and, striking one arm of the cranked lever "g", overcomes the force of the spring "s" and carries that arm of the cranked lever "g" downwards, carrying with it the valves "e" and "m" so that the mechanism is once again in the position shown in Figure 2 and is ready for another cycle.

I am aware that prior to my invention devices were used in which expanding gases were used for actuating mechanisms, also that internal combustion pumps were known and used; I therefore do not claim these broadly; but:—

I claim:

1. A device of the character described comprising a pair of compression chambers ported into communication, means for effecting compression of fluid in one of said chambers, a valve closing said port of communication with the second chamber arranged to open to admit fluid so compressed in the first chamber and to close upon the equalization of pressures in said chambers, a pressure fluid conduit extended outwardly from within the first chamber and ported into communication with said first chamber, a valve for closing said port, means within said first chamber normally effective to hold said valve closed, and mechanism cooperating with said port valves and controlled and operated by fluid pressure within said first chamber to main-

tain initially attained pressure in the second chamber during reduction of pressure in the first chamber to a point in determinate ratio to the pressure in the second chamber and thereafter automatically operative to open said conduit and second chamber port valves in order and subsequently effective to cause said valves to return to port closing positions.

2. A device of the character described comprising a pair of compression chambers ported into communication, means for effecting compression of fluid in one of said chambers, a valve closing said port of communication with the second chamber arranged to open to admit fluid so compressed in the first chamber and to close upon the equalization of pressures in said chambers, a pressure fluid conduit extending outwardly from within the first chamber and ported in communication with said first chamber, a valve for closing said port, means within said first chamber normally effective to hold said valve closed, and mechanism controlled by fluid pressure within said first chamber and operative thereby to maintain initially attained pressure in the second chamber during reduction of pressure in the first chamber to a predetermined point and thereafter automatically operative to move the valve of said conduit port to open the port and subsequently to operate the valve of the second chamber to vent the pressure fluid therein, said mechanism including an element movable by said reduction of pressure to permit the return of said port valves to initial position.

3. A device of the character described comprising a pair of compression chambers ported into communication, means for effecting compression of fluid in one of said chambers, a valve closing said port of communication with the second chamber arranged to open to admit fluid so compressed in the first chamber and to close upon the equalization of pressures in said chambers, said second chamber being expansible, a pressure fluid conduit extending outwardly from within said first chamber and ported into communication with said first chamber, a valve for closing said port, means within said first chamber normally effective to hold said valve closed, and mechanism within the first chamber interconnecting said conduit port valve and expansible chamber effective in response to fluid pressure within the first chamber to maintain the second chamber against expansion and the fluid therein at initially attained pressure and movable by reduction of fluid pressure within the first chamber to a predetermined point automatically to expand the second chamber and to open said conduit port, said movement being effective to open the valve of said second chamber to vent its pressure fluid, and said mechanism including an element movable by reduction in fluid

pressure to cause the return of said port valves to initially closed position.

4. A device of the character described comprising a pair of compression chambers ported into communication, means for effecting compression of fluid in one of said chambers, said second chamber of the pair comprising a cylinder having fixed and relatively movable portions, a valve closing said port of communication with the second chamber arranged to open to admit fluid compressed in the first chamber and to close upon the equalization of pressures in said chambers, a pressure fluid conduit extending outwardly from within said first chamber and ported into communication with said first chamber, a valve for closing said port, mechanism mounted within said first chamber to receive the pressure fluid therein and having connection with the valve for said conduit port and with the movable portion of the compression cylinder of said second chamber, said mechanism functioning in response to the pressure of fluid in the first chamber and up to a predetermined point in a reduction of the fluid pressure therein, to hold said conduit port valve closed and the movable portion of said cylinder against expansion to maintain the initially attained pressure in said cylinder, said mechanism automatically operating upon reduction of pressure within the first chamber below said predetermined point to permit expansion of said cylinder portion and consequent movement of said mechanism to open the conduit port valve, said mechanism cooperating by said movement with the port valve of said second chamber and cylinder to vent its pressure fluid.
5. A device of the character described comprising, an outer compression cylinder, means for effecting compression of fluid therein, a fluid pressure conduit extended outwardly from within said cylinder and ported into communication with said outer cylinder, a valve closing said port of communication, an inner compression cylinder within said outer cylinder, comprising a fixed cylinder head, a movable pressure cylinder mounted to slide thereon, a port in said head placing its cylinder in communication with the outer cylinder, a valve closing said port of communication arranged to open to admit fluid compressed in the outer cylinder and to close upon equalization of pressures in said outer and inner cylinders, an operating stem for said conduit port valve, a connection between said stem and said movable compression cylinder, means for admitting fluid pressure of the outer cylinder to act upon said conduit port valve and the movable cylinder connected with its stem to cause said pressure to seat said valve and to maintain said inner compression cylinder against expansion during a decrease in the fluid pressure in the outer

cylinder to a point providing less pressure upon said valve and the exterior of said inner cylinder than the initially attained pressure within said inner cylinder and mechanism normally tending to seat said conduit port valve and permitting the seating of the inner cylinder valve comprising a lever connected with the stem of said conduit valve and normally tending to move said valve in one direction and a gravity operating member normally tending to move by the pressure of fluid within said outer cylinder to an operative relation to said lever and automatically moving by reduction in fluid pressure in said cylinder to cooperate with said lever and move it in a reverse direction.
